THREAD GUIDE FOR SHOE UPPER LACING MACHINES

William A. Berry, Brockton, Mass., assignor to United Shoe Machinery Corporation, Paterson, N. J., a corporation of New Jersey

Application March 21, 1933, Serial No. 661,921

5 Claims. (Cl. 112—5)

The present invention relates to thread guiding devices, and as herein illustrated, is embodied in a machine for lacing together the eyeletted uppers of a shoe preparatory to lacing, which machine is of the type shown in the U. S. Patent No. 1,030,547, granted June 25, 1912, to W. A. Smith.

In the machine described in that patent, lacings are passed through the eyelets of a shoe upper by a series of needles on which a lacing cord is supported, and mechanism is provided for threading the needles before the lacing cord is applied to the shoe upper. The cord is supplied to the needle threading mechanism through a guide which permits the cord to move freely from the supply. Due to the construction of the machine, when a large, loosely twisted cord is employed as a lacing, considerable rotation is imparted to the cord between the guide for the cord and the needle threading mechanism which, if permitted to work backwardly along the cord through the guide, is likely to twist the cord until kinks are formed between the guide and the supply so as to block further movement of the cord into the machine.

The objects of the present invention are to provide means for preventing the rotation of a twisted cord within a lacing machine from forming kinks in the length of cord running from the supply to the machine, and to provide a novel and improved cord guiding device which is strong, durable, and which may readily be threaded with the cord in preparing the machine on which it is mounted for operation.

One feature of the invention contemplates the provision in a machine for lacing together the eyeletted uppers of a shoe, of a guide for the lacing cord, so arranged as to prevent the formation of kinks in the cord between the machine and the cord supply. As hereinafter described, the guide comprises a curved tubular member bent into circular form, and if desired, in order to permit the cord to be more readily engaged in the guide, a slot may be provided along the outer wall of the bent portion.

In the drawing, Fig. 1 is a plan view of the operating mechanism of a lacing inserting machine in which the present invention is embodied; Fig. 2 is a plan view on an enlarged scale of the thread guiding device illustrated in Fig. 1; Fig. 3 is a view in side elevation of the device shown in Fig. 2; and Fig. 4 is an end view of the device shown in Fig. 2, looking from the right.

In the construction shown in the drawing, the

cord, indicated at 10, is formed into a series of loops supported by a series of needles 12 mounted in the machine. The upper of a shoe is positioned on the machine by sliding the threaded needles through the eyelets in the upper, and a length of cord is passed through the loops held by the needles projecting through the eyelets.

The supply of cord to the machine comprises a suitable package such as a ball or reel 14 mounted on or near the machine. The length of cord, indicated at 15, is directed forwardly in passing from the supply to the machine, and then is conducted at right angles along and through the eye of a cord carrying needle 16 reciprocating with a slide 18 for applying the cord to the lacing needles 12 prior to the application of an upper thereto. The cord carrying needle also acts when the upper is positioned on the lacing needles 12, to pass the cord through the loops supported by the needles at the front of the upper. In passing through the cord loops on the lacing needles, the cord carrying needle conveys the cord to a gripper fixed to the right side of the machine, and to a rotary knot tying mechanism supported on a split shaft 20 and rotated by a gear 22 surrounding the shaft.

The slide 18 on which the needle is mounted is operated by connections to the main cam shaft 26 of the machine and reciprocates in a guideway 24. The needle slide 18 also carries a guide 28 for the cord. In reciprocating towards and from the grippers and knot tying mechanism of the machine, the cord carrying needle 16 tends to impart a rotation to the cord 10, due to the frictional engagement of the twisted strands of the cord in the needle eye. The cord passes always in the same direction through the needle eye, thereby causing the tendency to rotate the thread to always be in the same direction. As a result, the cord is twisted between the guide 28 and the needle eye, and this twist tends to work back through the guide 28 and form kinks in the length of cord 15 between the eye and the supply reel, which kinks catch on the guide and block further movement of the cord into the machine.

To prevent twisting of the length 15 of the cord between the guide 28 and the supply 14, and to insure that the cord shall pass freely from the supply to the needle, according to the present invention, a twist resisting device is applied to the guide 28. This twist resisting device comprises a curved tube 30 of sufficient size to permit free passage of the cord therethrough.

The tube of the twist resisting device is bent into circular form through at least part of a complete turn, and into engagement with itself, so that the entrance to the device is disposed at 5 an angle to the exit. The tubular part of the device is connected to the guide 28 by an integral threaded sleeve 32 at the exit end of the device which is screwed into a threaded portion 10 of the guide 28 concentric with the passage through the guide. The device may be secured at any angle by a lock nut 34 provided on the threaded sleeve 32.

To permit the cord to be readily engaged in the twist resisting device the curved portion 15 thereof is slotted at 36 along the outer wall of the curved portion so that the cord may be passed through the entrance end of the tube 30 and through the adjacent end of the slot 36. The end of the cord may then be passed through 20 the slot 36 at the end nearest the exit sleeve 32, and through the sleeve and guide 28. When the end of the cord extending through the guide 28 is drawn further into the machine, the length 25 of cord extending between the two ends of the slot 36 will automatically pass through the slot, displacement of the cord being prevented so long as the slightest tension on the cord is present. Preferably the engaging portions of the tube are joined together by soldering at 38.

30 The nature and scope of the invention having been indicated, and a particular machine in which the invention may be embodied having been described, what is claimed is:

1. A lacing machine having, in combination, 35 lace inserting and knot tying mechanism, means for applying cord to the lace inserting mechanism including a reciprocating eye-pointed needle through the eye of which the cord passes, a guide for the cord between the needle and the 40 cord supply, and twist resisting means having a passage, the entrance of which is disposed at an angle to the exit for preventing twist of the cord produced as it moves through the needle eye from kinking the cord entering the guide.

45 2. A lacing machine having, in combination,

lace inserting and knot tying mechanism, means for applying cord to the lace inserting mechanism including a reciprocating eye-pointed needle through the eye of which the cord passes, a guide for the cord between the needle and the cord supply, and a curved tubular member 5 bent into circular form back upon itself and connected to the guide for preventing twist of the cord produced as its moves through the needle eye from kinking the cord entering the 10 guide.

3. A lacing machine having, in combination, lace inserting and knot tying mechanism, means for applying cord to the lace inserting mechanism including a reciprocating eye-pointed 15 needle through the eye of which the cord passes, a guide for the cord between the needle and the cord supply, and a curved tubular member bent into circular form back upon itself and connected to the guide for preventing twist in the 20 cord produced as it passes through the needle eye from kinking the cord entering the guide, said tubular member having a slotted wall along the outside of the bend to facilitate threading.

4. A lacing machine having, in combination, 25 mechanism for forming and inserting a cord lacing through the eyelets of a shoe upper, and a twist resisting cord guide through which the 30 cord passes to said mechanism comprising a curved tubular member bent into circular form and provided with a slot in the bent portion in the 35 outer wall thereof to facilitate threading.

5. A lacing machine having, in combination, 40 mechanism for forming and inserting a cord lacing through the eyelets of a shoe upper, and a twist resisting cord guide through which the cord passes to said mechanism comprising a curved tubular member bent into circular form back into engagement with itself and provided 45 with a slot in the bent portion in the outer wall thereof to facilitate threading, and means for securing the engaging parts of the member together.
